UNITED STATES PATENT OFFICE

2,609,506

GASEOUS TUBE OSCILLATOR

Gerrit Jan Siezen, Eindhoven, Netherlands, assignor to Hartford National Bank and Trust Company, Hartford, Conn., as trustee

Application August 3, 1948, Serial No. 42,264
In the Netherlands August 14, 1947

7 Claims. (Cl. 250—36)

1

This invention relates to a circuit for generating alternating voltage with the aid of a source of direct voltage and the series-combination of a condenser and an inductance, the series-combination being periodically connected to the direct voltage supply, which connection is subsequently interrupted, whereupon the circuit constituted by the series-combination of the condenser and at least a part of the inductance is completed.

Known circuits of this kind exhibit several disadvantages, which will be explained more fully by reference to Figures 1 and 2 of the drawing.

The series-combination of the condenser 1 and the inductance 2 as shown in Fig. 1 (in which a resistance 3 represents the resistance which is invariably provided in such a circuit) of which one extremity is connected to the negative terminal of a battery 4 having a terminal voltage E, is connected at its other extremity, by means of a mechanic switch 5, alternately to the positive and the negative terminal of the battery 4.

Assuming that the mechanic switch 5 is operated at a frequency which equals the natural frequency of the series combination, hence

$$f = \frac{1}{2\pi} \sqrt{\frac{1}{LC} - \frac{R^2}{4L^2}}$$

in which C, L and R represent the capacity of the condenser 1, the inductance of the coil 2, and the value of the resistance 3, respectively.

If in this case the switch alternately makes contact at either of the positions during exactly a half-wave an electromotive force produced at the input of the series-combination exhibits a variation which is shown as a function of time by the full line *a* in Fig. 2.

As is well-known, this E. M. F. comprises a first harmonic having an amplitude

$$\frac{2E}{\pi}$$

which is indicated by the dotted line *b* in Fig. 2.

The frequency of this first harmonic equals the natural frequency *f* of the series-combination, so that the amplitude of the condenser voltage V will attain a value

$$V = \frac{2}{\pi} QE$$

in which

$$Q = \frac{\omega L}{R} = \frac{2\pi f L}{R}$$

the so-called quality factor of the circuit.

2

Consequently, if Q has a high value, which implies that the losses occurring in the series-combination are small, a high output voltage V may be obtained.

As disadvantages of such a circuit we may mention the following.

The mechanic switch exhibits inertia, so that the switching frequency and hence also the resonant frequency of the circuit is limited, which may result in excessive values of the inductance and the capacity.

Furthermore, the tuning of the switching frequency to the resonant frequency of the circuit causes difficulty, more particularly if the quality factor Q of this circuit is high and hence the width of the resonance curve is small.

Finally, a certain period of time is required for switching over from one position of the switch to the other, so that the current pulses through the switch are of a duration shorter than a half wave, which results in sparking during the switching operation.

The circuit according to the invention mitigates the said disadvantages and exhibits the characteristic that the direct voltage supply is connected to the series-combination of the condenser and the inductance by way of an element which is conductive in only one direction, whilst the circuit constituted by the series-combination of the condenser and at least a part of the inductance is likewise completed by way of such an element.

Some forms of the circuit according to the invention will now be explained more fully by reference to the accompanying drawings.

The circuit shown in Fig. 3, of which parts identical with those of Fig. 1 bear the same reference numerals, differs from the circuit shown in Fig. 1 by the provision of two rectifiers 6 and 7 in the supply circuit and in the short-circuiting circuit respectively.

The operation of the circuit will be explained more fully by reference to Fig. 4.

Fig. 4a shows as a function of time the variation of the voltage V set up at the condenser, whereas Figs. 4b and 4c show the variations of currents *i*₁ and *i*₂ indicated by arrows in Fig. 3, as a function of time in the stationary position.

If, at the moment *t*=*t*₁, the voltage V has a value *-V*₂ and if the switch 5 at this moment establishes the contact 8, the voltage V rises from *-V*₂ to + *V*₁ according to the first part of a damped harmonic oscillation which has the value +*E* as a zero line and of which the continuance is indicated by the dotted line *c* in

Figure 4a. At the moment $t=t_2$, the current i_1 tends to change its direction, but this is prevented by the rectifier 6, so that the voltage retains the value V_1 . During the period of time between the moment $t=t_3$ and $t=t_4$, the contact arm of switch 5 changes over from contact 8 to contact 9. Subsequently, the condenser discharges across the rectifier 7, whereby the voltage V decreases from $+V_1$ to $-V_2$ according to the first branch of a damped oscillation, which has the line $V=0$ as the zero line and of which the further variation is indicated by the dotted line d .

At the moment $t=t_5$, the current i_2 tends to change its direction, but this is prevented by the rectifier 7, so that the voltage V remains $-V_2$ until the switch again changes its position.

For the values V_1 and $-V_2$, between which the voltage V varies when the stationary position is attained, we may simply find:

$$V_1 = \frac{E}{1 - e^{-\frac{\pi}{2Q}}}$$

$$V_2 = \frac{Ee^{-\frac{\pi}{2Q}}}{1 - e^{-\frac{\pi}{2Q}}}$$

For a high value of Q is then found approximately:

$$V_1 \approx V_2 \approx \frac{2}{\pi} QE$$

so that the amplitude of the alternating voltage set up across the condenser approximately equals that which occurs in a known circuit as shown in Figure 1. However, in practice it will appear that the voltage produced has a slightly lower value as a result of the internal resistance of the rectifiers which bring about higher damping.

Consequently, in this circuit the frequency of the mechanic switching operation may be chosen to be considerably lower than the resonance frequency of the series-combination, so that the latter may be given a high value, which permits of obtaining a higher value of the quality factor Q .

Figure 4 furthermore shows that half the periodic time of the series-combination extends, for example, from t_1 to t_2 or from t_4 to t_5 , whilst the time during which the switch occupies the position 8 or 9 extends from t_1 to t_3 or from t_4 to t_6 respectively.

The periods during which the switching arm moves from one position to the other correspond to the periods t_3-t_4 and t_6-t_7 .

In this circuit, however, during the periods in which the rectifiers 6 and 7 are conductive, the switching arm acquires a voltage equal to the instantaneous value of the condenser voltage, that is $+V_1$ or $-V_2$, so that the rectifiers are required to resist a high blocking voltage and sparking still occurs in the contact-making of the switching arm.

A further advantageous form of the circuit according to the invention does not exhibit this disadvantage, whilst furthermore the mechanic switch is omitted.

In such a circuit, which is shown in Fig. 5, use is made of gas-filled discharge tubes 10 and 11. In this case it is possible to provide that the switching operation is performed wholly automatically under the action of the natural oscillation of the resonant circuit.

The igniting and operating voltages of the dis-

5
10

charge tubes are required to be such that alternately one of the tubes is conductive whilst for the automatic starting of the circuit it is furthermore necessary that the igniting voltage of tube 10 should be lower than the battery voltage E , since otherwise ignition does not take place when condenser 1 is uncharged.

If:

V_{010} is the igniting voltage of tube 10

V_{011} is the igniting voltage of tube 11

V_{b10} is the operating voltage of tube 10 and

V_{b11} is the operating voltage of tube 11

the above-mentioned conditions are fulfilled if:

$$E - V_{b10} < V_{011} \quad (1)$$

$$E - V_{010} < V_{b11} \quad (2)$$

and

$$V_{011} < E \quad (3)$$

The operation of the circuit may appear from Fig. 4, which, as before, shows the stationary waveform.

Starting from the voltage $-V_2$, the condenser voltage, if tube 10 is conductive, will again rise to the voltage V_1 , tube 11 then being inoperative on the ground of relation (1). As soon as the voltage V_1 is attained, the current i_1 will inverse its polarity, whereby tube 10 extinguishes. The voltage at the point 12 in Fig. 5 will then rapidly increase, since the condenser voltage has a high value, but as soon as the voltage at the said point has reached the value V_{011} , tube 11 will ignite, so that the condenser voltage decreases to the value $-V_2$. Tube 10 remains inoperative during this period on the ground of condition (3). When V attains the value $-V_2$, the current i_2 will change its polarity, so that tube 11 extinguishes. The voltage at the point 12 then rapidly decreases since the condenser voltage is negative, but as soon as the voltage at this point reaches the value $E - V_{010}$, tube 10 reignites and the cycle described is repeated.

The value of the voltage at point 12 evidently varies between the values $E - V_{b10}$ and V_{b11} . Consequently, only the part ΔE of the battery voltage E is effectively used for the excitation of the circuit, given by:

$$\Delta E = E - V_{b10} - V_{b11} \quad (4)$$

From this it follows with (1) and (2):

$$\Delta E < V_{011} - V_{b11} \quad (5)$$

$$\Delta E < V_{010} - V_{b10} \quad (6)$$

so that ΔE is always smaller than the difference between the igniting and operating voltages of the discharge tubes used. The amplitude of the alternating voltage V set up at the condenser,

$$V = \frac{2}{\pi} Q \Delta E$$

65 is thus always smaller than

$$\frac{2}{\pi} Q (V_{010,11} - V_{b10,11})$$

70 In order to ensure a maximum difference between the igniting and operating voltages, it is advantageous to utilise gas-filled discharge tubes each comprising a control-grid which is suitably biased in such manner that the igniting voltage of the tubes has a high value. Such tubes fre-

quently have a low operating voltage so that a high potential difference may be obtained.

One form of such a circuit is shown in Figure 6.

In this case each of the gas-filled discharge tubes 13, 14 comprises a control grid 15, and 16 respectively, to which a negative voltage is supplied across resistances 17 and 18 respectively, which permit of adjusting the igniting voltage of the tubes. If the operating voltages Vb_{13} and Vb_{14} have small values, the voltage

$$\Delta E = E - Vb_{13} - Vb_{14}$$

is available for the excitation of the circuit, which voltage may be substantially equal to E .

If, for example, the igniting voltage V_{014} of tube 14 is chosen to be substantially equal to E , then it follows from conditions analogous to (2) and (3) that $E - Vb_{14} < V_{013} < E$.

If Vb_{14} has a small value, the adjustment of the igniting voltage V_{013} is comparatively critical, which may be avoided, however, by connecting the point 19 to a negative potential $-V_0$, which results in the condition

$$V_{013} < E + V_0$$

Consequently, the igniting voltage of tube 13 may be chosen between two further different values, viz. $E - Vb_{14}$ and $E + V_0$.

Furthermore, it may be observed that it is advantageous, in order to avoid additional damping, to utilise tubes having a minimum internal resistance.

Very satisfactory results may be obtained if use is made of tubes exhibiting a declining current-voltage characteristic curve over as large a current region as possible, such as shown, for example, in Figure 7. Here the voltage of the tube is plotted against the current traversing the tube, the characteristic curve exhibiting a declining variation as a function of the current strength i through the tube between the igniting voltage V_a and the operating voltage V_b .

As long as the portion $V_a - V_b$ of the characteristic curve is traversed, a damping-reducing action will be exerted on the resonant circuit.

The circuits shown in Figs. 5 or 6 may, furthermore, exhibit the drawback that as a result of the time required for the ionisation of the discharge tube, upon the extinction of one of the tubes and the ignition of the other, the first-mentioned tube reignites, so that short-circuit of the battery would occur.

Some examples of circuits in which this disadvantage is also suppressed will be described by reference to Figs. 8, 9 and 10.

The circuit shown in Fig. 8 only differs from that shown in Fig. 6 in that inductances 20 and 21 are included between the cathode of tube 13 and the point 19 and between the anode of tube 14 and the point 19 respectively.

As soon as tube 13 extinguishes and tube 14 ignites the cathode of tube 13 acquires a positive increase in voltage since the voltage V at this moment has a high positive value. Consequently, more rapid deionisation occurs in tube 13.

Conversely, a decrease in anode voltage after the extinction takes place in tube 14, which also results in more rapid deionisation in this tube.

If the voltages set up across the tubes are called V_{13} and V_{14} with the polarities shown in the figure, and if the inductances of the coils 20 and 21 are L_{20} and L_{21} respectively and that of the coil 2 is L_2 , we have, if tube 13 is conductive;

$$V_{13} = Vb_{13}$$

$$V_{14} = \frac{L_2}{L_{20} + L_2} (E - Vb_{13}) + \frac{L_{20}}{L_{20} + L_2} V$$

and if tube 14 is conductive:

$$V_{14} = Vb_{14}$$

$$V_{13} = E - \frac{L_2}{L_{21} + L_2} Vb_{14} - \frac{L_{21}}{L_{21} + L_2} V$$

- 10 The voltages V_{13} and V_{14} thus acquire a component which is proportional to V and which is always of a polarity such that a decrease occurs immediately after extinction. This component must not bring about ignition at the end of the period concerned, when V changes its polarity, which may be ensured by adjusting the igniting voltages to sufficiently high values by means of the control-grid voltages. Since the voltage V has a value very much higher than the voltage E , the values of the inductances L_{20} and L_{21} may be chosen to be small with respect to the value L_2 .

In the circuit shown in Figure 9, rapid deionisation of the gas-filled discharge tubes is also obtained subsequent to the extinction of the tubes.

25 In this case, however, it is not the whole series-combination of the condenser and the inductance, but only a part, viz. the condenser and a part of the inductance, which is included in the discharging circuit of the condenser.

The part 25 of the coil 23 forms in this circuit only part of the charging circuit, whereas the remaining part 24 is included in both the charging and discharging circuits of the condenser 22.

30 The series-combination further comprises, as before, the usual damping resistance 26. The discharge tubes 27, 28 are of the gas-filled type, as before, and their control grids are suitably biased by way of resistances 29 and 30.

35 If the inductance of the coil 23 is L_{23} and the inductance of the part 24 of this coil is $n^2 L_{23}$, and if the voltages set up across the discharge tubes are V_{27} and V_{28} respectively, we have:

if tube 27 is conductive:

$$V_{27} = Vb_{27}$$

$$V_{28} = n(E - Vb_{27}) + (1 - n)V$$

in which V satisfies the differential equation:

$$L_{23} C_{22} \frac{d^2 V}{dt^2} + V = E - Vb_{27}$$

if tube 28 is conductive:

$$V_{28} = Vb_{28}$$

$$V_{27} = E - nVb_{28} - (1 - n)V$$

55 while

$$n^2 L_{23} C_{22} \frac{d^2 V}{dt^2} + V = Vb_{27}$$

With reference to the above equations and in view of the conformity with those deduced for the circuit shown in Fig. 8, it will be evident that the faster deionisation aimed at is also ensured in this circuit.

60 If in the circuit shown in Fig. 8, L_{20} is chosen to be equal to L_{21} , the angular frequency occurring at the rising cosinus branch of the voltage V equals that with the declining branch. If, however, L_{20} and L_{21} are chosen to be different, a difference in velocity occurs in the increase and decrease of the voltage with the result that the voltage V acquires a sawtooth character.

65 Such a variation of the voltage V as a function of the time t is shown in Fig. 10. Here a rapid decrease in voltage occurs during the period of time $t_1 - t_2$ in which tube 14 of Fig. 8 is conduc-

70

tive, which decrease in voltage is followed by a slowly increasing voltage during the period of time t_2-t_3 , in which tube 13 is conductive.

From the two differential equations deduced for the circuit shown in Fig. 9, it follows that a sawtooth voltage V automatically occurs, since the angular frequency for the rising branch is n -times that of the declining branch.

The so-called feedback ratio of the sawtooth voltage thus equals the ratio n in which the coil 23 is divided.

What I claim is:

1. An alternating voltage generator comprising a source of direct voltage of predetermined magnitude, first and second gaseous discharge devices, an oscillatory network constituted by an inductive element connected in series with a capacitance, said network being connected through said first device to said source, and means connecting said second device between the end of said capacitance remote from said element and a point in said element, said first device having a value of ignition voltage which is less than said predetermined magnitude and having a prescribed value of operating voltage, said second device having a value of ignition voltage relative to that of said first device and a value of operating voltage relative to that of said first device at which said devices are automatically rendered alternately conductive.

2. An arrangement, as set forth in claim 1, wherein said network further includes a resistance interposed between said capacitance and said element.

3. An arrangement, as set forth in claim 1, wherein said devices are each characterized by a declining-current-voltage characteristic curve between the ignition and operating voltage.

4. An alternating voltage generator comprising a source of direct voltage of predetermined magnitude, first and second gaseous discharge devices, an oscillatory network constituted by a capacitance connected in series with an inductance element formed by first and second serially-connected inductors, said network being connected through said first device to said source, a third inductor, and means connecting said second device between the end of said capacitance remote from said element and through said third inductor to the junction of said first and second inductors, said first device having a value of ignition voltage which is less than said predetermined magnitude and having a prescribed value of operating voltage, said second device having a value of ignition voltage relative to that of said first device and a value of operating voltage relative to that of said first device at which said devices are automatically rendered alternately conductive.

5. An arrangement, as set forth in claim 4, wherein said first and third inductors are of different value.

6. An alternating voltage generator comprising a source of direct voltage of predetermined magnitude, first and second gaseous discharge devices, an oscillatory network constituted by a capacitance connected in series with an inductive element formed by a single inductor, said network being connected through said first device to said source, and means connecting said second device between the end of said capacitance remote from said inductor and an intermediate tap in said inductor, said first device having a value of ignition voltage which is less than said predetermined magnitude and having a prescribed operating voltage, said second device having a value of ignition voltage relative to that of said first device and a value of operating voltage relative to that of said first device at which said devices are automatically rendered alternately conductive.

7. An alternating voltage generator comprising a source of direct voltage of predetermined magnitude, first and second gaseous discharge devices each having a cathode, an anode and an ignition electrode, an oscillatory network constituted by a capacitance connected in series with an inductive element, means connecting the anode of the first device to the positive terminal of the source and the cathode thereof to the free end of said element, the free end of said capacitance being connected to the negative terminal of said source, means connecting the cathode of said second device to the free end of said capacitance and the anode thereof to a point in said element, means to apply a bias to the ignition electrode of said first device at which the resultant value of ignition voltage for said first device is less than said predetermined magnitude, and means to apply a bias to the ignition electrode of said second device at which the resultant value of ignition voltage for said second device relative to the value ignition voltage of said first device causes said devices to become alternately conductive.
